UNITED STATES PATENT OFFICE.

FREDRICK W. MOORE, OF PROVIDENCE, RHODE ISLAND.

DESIGN FOR A NECKLACE.

SPECIFICATION forming part of Design No. 15,915, dated March 3, 1885.

Application filed January 13, 1885. Term of patent 3½ years.

To all whom it may concern:

Be it known that I, FREDRICK W. MOORE, of the city and county of Providence, and State of Rhode Island, have produced a new 5 and ornamental Design for Necklaces, of which the following is a full, clear, and exact description, reference being had to the accompanying drawing, forming a part of this specification.

10 This design relates to the fronts of necklaces; and the leading feature of the design is a divided crescent-shaped front piece, as hereinafter described.

The figure illustrates my design as connected 15 with a chain and having its two parts united by chain-links, from which a locket is suspended between the sections of the front piece.

15 a designates the chain which is intended to 20 encircle the neck. a' designates the links which

unite the two front-piece sections, and b designates a locket suspended from links a' and lying between the sections of the front piece.

B B designate the two sections which form the front piece, and each of which is broader 25 at the end contiguous to the locket and tapers to a point at the opposite end, so that when viewed together they present the appearance of a crescent divided transversely at its greatest width.

Having thus described my new and original 30 design, I claim as new and desire to secure by Letters Patent—

The design for a necklace, consisting of the two sections B B, connected by the links a', 35 and the pendant or locket b, as set forth.

FREDRICK W. MOORE.
